Inventor,
James M. Beatty.

UNITED STATES PATENT OFFICE

2,282,555

TOY RING GAME

James M. Beatty, Brooklyn, N. Y.

Application October 29, 1940, Serial No. 363,279

3 Claims. (Cl. 273—99)

This invention relates to small hand toys and particularly to a ring game and has for its objects to provide a simple, efficient and inexpensive toy ring game.

An object of this invention is to provide a whirling-motion game comprising an axle having an annular indicia disk rotatably mounted at the upper portion of said axle and having a ring-shaped target secured by a flexible string to said disk for rotating said disk when the axle is whirled with its lower end in fixed position in the hand of the user and its upper end motivated in a circular orbit.

Another object of this invention is to provide an inverted dish-shaped casing fixed to the upper end of the axle and having a sight opening through which the indicia on the rotatable disk may be viewed.

Another object of this invention is to provide a pin projecting from the upper end of the casing and serving as a receiver for the ring-shaped target.

With the above and other objects in view, the invention will be hereinafter more particularly described, and the combination and arrangement of parts will be shown in the accompanying drawing and pointed out in the claims which form part of this specification.

Reference will now be had to the drawing, wherein like numerals of reference designate corresponding parts throughout the several views, in which:

Figure 1 is a central longitudinal cross-sectional view of the toy ring game.

Figure 2 is a front elevation of the device.

Figure 3 is a top plan view of a casing having a sight opening.

Figure 4 is a bottom view of the casing and an indicia disk rotatable therein.

Figure 5 is a top plan view of the indicia disk.

In the illustrated embodiment of the invention, the numeral 1 indicates a handle or axle which is preferably made of wood and has a cylindrical upper end portion 2 of smaller diameter than its lower end. The cylindrical end portion 2 provides a bearing for an annular dial member 5 rotatably mounted thereon by means of a central aperture 17 adapted to freely engage the cylindrical upper end portion 2. The annular dial member 5 preferably has an annular plate 9 secured to its upper surface. The plate 9 has a centrally positioned aperture 17 providing passage therethrough for the upper end 2. The plate 9 is preferably provided with triangular

indicia circumferentially positioned on its upper face to cover the entire surface thereof.

Secured by gluing to the reduced upper end 2 of the axle 1 is an elongated cylindrical extension 1A having a pointed upper end 4. The lower end of the extension 1A is in spaced relation from the plate 9 to permit attachment to said axle of an inverted dish-shaped casing 6. The casing is of sufficient height to extend to the bottom of the dial member 5. The casing is secured to the portion 2 by nails 10.

The base portion of the casing 6 has a sight opening 7 preferably of modified trapezoidal form and having two radially positioned side walls. The radial side walls are adapted to align with the radial walls of the triangularly shaped indicia on the annular plate 9. The casing 6 has a centrally positioned clearance aperture 16 providing passage therethrough for the upper end 2 of the axle 1.

Painted on the plate 9 are twelve variously colored sections, nine of which are of equal area and are identified by the numerals 18, 19, 20, 21, 22, 23, 24, 25 and 26. Three of the twelve sections 27a, 27b and 27c are of smaller area and jointly equal the area of one of the said nine sections.

The large sections 20, 23 and 26 are colored red. The large sections 19, 22 and 25 are colored white. The large sections 18, 21 and 24 are colored blue. The small sections 27a, 27b and 27c are respectively colored blue, white and red.

A rubber target 15 preferably in the form of a ring, is secured at its lower end to a flexible cord 13 by suitable clamping means 14. The upper end of the cord 13 is secured to the lower surface of the annular member 5 by suitable clamping means 11 and 12.

In operation, the user grips the lower end of the handle or axle 1 and turns or rotates the upper end thereof in a circular orbit. The weight of the target 15 causes the dial members 5 and 9 to rotate. After the operator has rotated the dial member about three times, he stops turning the handle and tries to catch the rubber ring target 15 on the pointed end 4. The chance showing of a particular color or colors in the sight opening 7 is counted as a number of points. A full showing of a red colored section or a white colored section or a blue colored section counts as five points. A showing of two differently colored sections counts as three points. A showing of three colored sections counts as ten points.

In accordance with the patent statutes I have described and illustrated the preferred embodiment.

ment of my invention, but it will be understood that various changes and modifications can be made therein without departing from the spirit of the invention as defined by the appended claims.

I claim:

1. In a whirling-motion game, comprising an axle adapted to be gripped in the hand, said axle having a reduced upper end providing a bearing, an annular dial member having triangular indicia on its upper surface and being rotatably mounted on said bearing, said indicia being successively differently colored, an inverted dish-shaped casing fixed to said reduced upper end portion of said axle and having a trapezoidal sight opening at its upper surface, said annular indicia member being of smaller diameter than said dish-shaped casing to permit rotation thereof within said casing, said indicia being circumferentially positioned and adapted to successively come into view in said sight opening, said rotatably mounted indicia member having a ring-shaped target secured thereto by a flexible string, said indicia member being adapted to rotate and acquire momentum when said axle is whirled with its lower end in fixed position in the hand of the user and its upper end motivated in a circular orbit.
2. In a whirling-motion game, comprising an axle adapted to be gripped in the hand, said axle having a reduced upper end providing a bearing, an annular dial member having indicia on its upper surface and being rotatably mounted on said bearing, said indicia being successively differently colored, an inverted dish-shaped casing fixed to said reduced upper end portion of said

axle and having a sight opening at its upper surface, said annular indicia member being of smaller diameter than said dish-shaped casing to permit rotation thereof within said casing, said indicia being circumferentially positioned and adapted to successively come into view in said sight opening, said rotatably mounted indicia member having a ring-shaped target secured thereto by a flexible string, said indicia member being adapted to rotate and acquire momentum when said axle is whirled with its lower end in fixed position in the hand of the user and its upper end motivated in a circular orbit, and an elongated extension projecting from the upper face of said casing serving as a receiver for said ring-shaped target.

3. In a whirling-motion game, comprising an axle adapted to be gripped in the hand, said axle having a bearing, an annular dial member having indicia on its upper surface and being rotatably mounted on said bearing, said indicia being successively different from each other, an inverted dish-shaped casing fixed to said reduced upper end portion of said axle and having a sight opening at its upper surface, said annular indicia member being of smaller diameter than said dish-shaped casing to permit rotation thereof within said casing, said indicia being adapted to successively come into view in said sight opening, said rotatably mounted indicia member having a ring-shaped target secured in spaced relation therewith, whereby said indicia member is set in motion when said axle is whirled with its lower end in fixed position in the hand of the user and its upper end is moved in a circular orbit.

JAMES M. BEATTY.
